WATER TREATING APPARATUS

Owen L. Appleby, San Jose, Calif.

Application August 16, 1933, Serial No. 685,353

5 Claims. (Cl. 122—183)

The present invention relates particularly to means for removing the scale forming mineral matter from water during its conversion into steam for use in sterilizing or for other purposes.

5 It is the object of the present invention to provide a means of the character indicated that will be economical to manufacture, simple in form and construction, that consists of few parts quickly and easily assembled, and disassembled 10 for cleaning, strong, durable, and highly efficient in its practical application.

In the drawing:

Figure 1 is a longitudinal section through a structure embodying my invention, partly in elevation, and with parts broken away.

Figure 2 is a section on line 2—2 of Figure 1.

Figure 3 is a section on line 3—3 of Figure 1.

In the particular embodiment of the invention herein disclosed, I show at 1 a fire-box with the 20 combustion chamber at 2 and a fuel oil burner at 3 discharging into chamber 2. A vertically disposed cylindrical housing 4 is mounted over chamber 2, with a cap 5 through which the products of combustion are discharged.

25 At 6 is shown a hollow steel cylinder having its lower end closed but having a top closure 7 bolted thereto as at 8.

Passing axially through closure 7 and welded thereto is a pipe 9. This pipe passes down to a 30 point adjacent the bottom of the cylinder, where it is fitted with a terminal portion 10 through the medium of a union as 11, this end portion being formed to discharge the water in such a manner as to impart a circular motion thereto.

35 Slidably mounted on pipe 9, and slidably engaging cylinder 6, are a plurality of discs as 12 spaced apart to form annular chambers as 13. A spring as 14 is fitted between the topmost disc and the closure 7, so that when the discs are all

40 in place and the part 10 in position the central portions of the discs are in frictional engagement and held against accidental turning, yet the discs may be rotationally adjusted as desired. Each disc has a passage as 15 formed in its edge. When 45 the discs are all adjusted as desired on the pipe 9 the passages 15 in the successive discs are offset in the same direction as indicated at 15 to 15g, the successive passages thereby forming a continuous helicoidal passage through which the

50 water discharged into the bottom of the cylinder flows to the top thereof. However, due to the spacing of the several discs and the angular direction of the water flow, slow eddy currents are set up in each chamber 13, there being a continuous, but slow, movement of water completely

around each chamber 13 as indicated by arrow 16.

The supply pipe 9 is connected to a fitting 17 to which are also connected a pipe portion 18 with a union at 19, and pipe portions 20—21, these latter two portions merely overhanging the top edge 22 of the cylinder housing and cooperating with part 18 to suspend the cylinder 6 in the housing as shown.

At 23 is shown a portion of a discharge pipe 10 communicating with the interior of cylinder 6 and welded to the closure 7. This pipe portion is connected by a union 24 to a coil of pipe 25 that 15 encompasses cylinder 6, passing downwardly to a point adjacent the bottom thereof and then upwardly as shown at 26 and outwardly as at 27 20 where it is fitted with a union 28.

When the device is in operation the water discharged into the lower end of cylinder 6 is rapidly converted into steam as it flows through the cylinder as above described. In this tortuous 20 and slow passage, however, the scale forming minerals are deposited in the several chambers 13 and the coil 25 is kept entirely free of such 25 deposits.

To clean the scale out it is only necessary to disconnect the unions 19 and 28 whereupon the 30 whole structure may be lifted out of housing 4. By removing the bolts 8 and disconnecting union 24 after the structure has been lifted out of housing 4 as above described the cylinder 6 may 35 be separated from coil 25 and removed from the disc assembly, thereby permitting them to be easily cleaned of the scale.

It is to be understood, of course, that while I have herein shown and described but one specific 35 embodiment of the invention, changes in form, construction, and method of assembly and operation may be made within the scope of the appended claims.

I claim:

1. A device of the character described comprising, a plurality of coaxially disposed substantially closed annular chambers provided with connecting passages annularly offset to define a helical path of travel for water passed therethrough. 45

2. A device of the character described comprising, a plurality of coaxially and contiguously disposed and substantially closed annular chambers provided with connecting passages annularly offset to define a helical path of travel for water 50 passed therethrough.

3. A device of the character described comprising, a cylindrical drum having means for introducing water into one end thereof and a discharge outlet for the other end thereof, a series of spaced 55

plates coaxially disposed therein to form a series of annular chambers, each plate having a passage formed therethrough, the passages in the several plates being offset to form a helical path of travel for the water passing therethrough.

5 4. A device of the character described comprising, a combustion chamber, a steam chamber disposed therein with one end directed toward the source of heat, and a water conduit leading into the steam chamber and discharging in said end, said steam chamber having an outlet at the end remote from the first mentioned end and having a sequence of communicating smaller chambers disposed therein, the communication between each two of the smaller chambers being 10 annularly offset with relation to the communication between the preceding chambers.

5 5. A device of the character described comprising, a combustion chamber, a steam chamber disposed therein with one end directed toward the source of heat, a water conduit leading into the steam chamber and discharging in said end, said steam chamber having an outlet at the end remote from the first mentioned end and having a sequence of communicating smaller chambers disposed therein, the communication between each two of the smaller chambers being 10 annularly offset with relation to the communication between the preceding chambers, and a conduit connected to the steam chamber outlet and encircling said chamber in the direction of the source of heat and then leading out of the combustion chamber. 15

OWEN L. APPLEBY.
